EDWARD R. SARGENT, OF NEW HAVEN, CONNECTICUT, ASSIGNOR TO SARGENT & COMPANY, OF NEW HAVEN, CONNECTICUT, A CORPORATION OF CONNECTICUT.

CASKET-HANDLE.

1,241,287.

Specification of Letters Patent. Patented Sept. 25, 1917.

Application filed September 14, 1916. Serial No. 120,090.

To all whom it may concern:

Be it known that I, EDWARD R. SARGENT, a citizen of the United States, residing in the city and county of New Haven and State 5 of Connecticut, have invented certain new and useful Improvements in Casket-Handles, of which the following is a full, clear, and exact description.

This invention relates to casket handles, 10 and more particularly to those constructed of sheet metal. The invention also pertains especially to handles of the type in which an arm adapted to support an elongated bar is pivoted within a hollow sheet metal socket 15 plate.

One of the primary objects of the invention is to provide simple and efficient means for pivoting the arm within the socket plate in an improved manner.

Another object of the invention is to reduce the number of parts, facilitate the method of manufacture, and produce an article of strong, durable but very inexpensive construction.

To these and other ends, the invention consists in the novel features and combinations of parts to be hereinafter described and claimed.

In the accompanying drawing,

Figure 1 is a front elevation of a casket handle embodying my improvements, with the handle bar omitted;

Fig. 2 is a rear elevation of the handle shown in Fig. 1;

Fig. 3 is a side elevation with certain parts broken away, the arm being in the raised position;

Fig. 4 is a rear view similar to Fig. 2, showing the arm in the raised position;

Fig. 5 is a detail section on line 5—5 of Fig. 4; and

Fig. 6 is a detail fragmentary rear view of the socket plate with the arm detached.

In the particular construction illustrated, 45 the handle comprises a socket plate 6 pivotally supporting an arm 7, which is provided at its lower end with a socket 8 for a handle bar of well-known type (not shown). The socket plate 6 is stamped up 50 of sheet metal with a turned-in edge as customary in many handles, thereby creating a hollow space 9 at the back of the plate, and said plate is provided with the usual

holes 10 for the passage of screws which secure the plate to the casket, box or other 55 article. The arm 7 extends through an opening 11 cut in the lower central part of the socket plate, and is pivoted to the plate at the rear of the front wall of the latter, as hereinafter described.

In the particular form shown, the arm 7 is substantially U-shaped in cross-section, thereby presenting parallel rearwardly extending walls 12. The opening 11 in the socket plate is of rectangular form and of 60 such size and shape as to receive the arm 7 with a rather snug fit, the side walls 12 of the arm being close to the side edges of said opening. At the upper part of the arm, the same is of less depth than at the lower part, 65 and each of the walls 12 is formed at its upper extremity with a hook-shaped abutment 13. The metal at the side edges of the opening 11 is turned in to present parallel rearwardly extending walls 14 to which the 70 arm is pivoted by a pivot pin 15. At the upper part of each of the walls 14, a notch 16 is provided for receiving the pivot pin, 75 said notches being open at the rear edges of the respective walls.

In assembling the handle, the arm is thrust through the opening 11 until its rear end is some distance back of the walls 14. The pivot pin 15 is then passed transversely through the inner end of the arm, for which 80 purpose the walls 12 of the arm are provided with registering perforations 17. In the particular form shown, these perforations 17 are located closely adjacent the hook-shaped abutments 13. The pin 15 is of such length 85 and so placed in the arm that its end portions extend laterally beyond the respective sides of the arm. The pin being located in the inner end of the arm, the latter is drawn forwardly so as to pull the projecting ends 90 of the pin into the respective seats or notches 16. The pin is then suitably locked in the notches, for example, by bending the portions of the walls 14 adjacent the notches so as to produce small hooks 18 which 95 permanently hold the pivot pin in the notches. Thus, the arm is pivoted between the walls 14 of the socket plate in a simple but substantial manner.

When the parts are in the assembled position, the pivot pin 15 is effectively pre-

vented from longitudinal displacement by the contour given to the front wall of the socket plate. It will be observed that this wall is bent inward at 6° to present inwardly extending portions which lie close to and opposite the respective end surfaces of the pin. These portions, therefore, constitute abutments to limit the play of the pin in an endwise direction, and as a consequence it is unnecessary to provide special means for locking the pin against movement longitudinally thereof in the notches or seats 16.

When the handle is in use, the arm is raised to the position shown in Fig. 3. In this position, the hook-shaped abutments 13 at the inner end of the arm come into contact with coöperating abutments 19 on the respective walls 14. These abutments or stops 19 may be conveniently formed by indenting the metal of the walls 14, as shown. In other words, opposite portions of the walls 14 are bent inwardly toward each other until they are in such a position as to lie in the path of the hooks 13 when the arm is raised, as shown particularly in Fig. 4. The stop projections 19 do not, however, interfere with the movement of the arm into the assembled position, as that portion of the arm which is located opposite these projections is shaped so as to clear the same. The abutment of the hooks 13 against the projections 19 takes up a part of the strain of lifting the box or other article when the arm is in the operative position. At this time, a portion of the front surface of the arm abuts the upper edge of the opening 11, as indicated at 20 in Fig. 3, and thus the strain is received at this point also. By taking up the strain at these two different points, it is effectively and evenly distributed.

It will be apparent from the foregoing description that with my improved construction, the number of parts is reduced to a minimum, and that the improved handle while very strong and durable may be manufactured at a low cost.

Without limiting myself to the precise construction shown, I claim:

50 1. In a casket or like handle, the combination of a sheet metal socket plate having an opening with inturned edges, a pin extending between the inturned edge portions of said opening and mounted therein, said pin lying at the rear of the front wall of said plate, a separate arm pivoted to the plate by means of said pin and extending through said opening, and means bent up from the front wall of the plate adjacent the ends of the pin for preventing longitudinal displacement of the latter; substantially as described.

2. In a casket or like handle, the combination of a sheet metal socket plate having an opening therein and parallel inwardly

extending walls turned in from the body of the socket plate at the respective sides of said opening, the inner edges of said walls having notches therein, a pin engaging said notches and extending across said opening 70 and clenched in said notches to prevent lateral movement out of the same, means adjacent the end of the pin for preventing lengthwise movement thereof, and a separate sheet metal arm passing through said opening and having side walls through which said pin is passed, said arm pivoted to said plate by means of said pin; substantially as described.

3. In a casket or like handle, the combination of a sheet metal socket plate having an opening therein and inwardly extending substantially parallel walls formed integral with said plate at the respective sides of said opening, said walls formed to present stops, 85 a pin engaging said walls and extending therebetween, and a separate arm in said opening pivoted to said plate by means of said pin and having parts to coöperate with said stops, substantially as described. 90

4. In a casket or like handle, the combination of a sheet metal socket plate having an opening and parallel inwardly extending walls with notches at the inner edges thereof, a pin extending between and engaged in said notches, the walls of said notches being bent to close the same and prevent rearward movement of said pin out of said notches, said plate being bent rearwardly adjacent the ends of said pin for preventing endwise 100 movement of the pin, and a separate arm located between said parallel walls and pivoted to said plate by means of said pin; substantially as described.

5. In a casket or like handle, the combination of a sheet metal socket plate having an opening in the front wall thereof with inwardly extending parallel side walls at the side edges of said opening, said inwardly extending walls having notches at their inner edges, a transverse pin extending between said walls and fitting in said notches, said notches being closed to retain the pin therein, said plate having bent portions in its front wall adjacent the respective ends 110 of said pin, so as to limit the longitudinal movement of the latter, and an arm extending through said opening in the socket plate, and through which said pin is passed transversely, the inner end of said arm having 115 abutments, and stops formed on said inwardly extending walls below said pin to coöperate with said abutments; substantially as described.

6. In a casket or like handle, the combination of a socket plate having an opening with inturned edge portions at the sides, said edge portions having integral stops, an arm pivoted to said plate within said opening and above said stops, and means on the 120 125 130

arm to coöperate with said stops; substantially as described.

7. In a casket or like handle, the combination of a socket plate having an opening with opposite inturned edge portions at the sides, said edge portions indented to present stops extending toward each other, an arm

pivoted to said plate within said opening and above said stops, and hook-shaped abutments on the arm to coöperate with said stops; substantially as described.

In witness whereof, I have hereunto set my hand on the 13th day of September, 1916.

EDWARD R. SARGENT.
